United States Patent

Des. 238,751

Patented Feb. 10, 1976

238,751

DISPENSING CONTAINER FOR VITAMINS OR THE LIKE

Gregory Scott MacGrossen, Manhattan Beach, Calif.,
assignor to Photographic Marketing Corporation of
America, Hermosa Beach, Calif.

Filed Aug. 23, 1973, Ser. No. 390,886

Term of patent 14 years

Int. Cl. D9—01

U.S. Cl. D9—18

FIGURE 1.

FIGURE 2.

FIGURE 3.

FIGURE 4.

FIG. 1 is an exploded perspective view of a dispensing container for vitamins or the like, showing my new design;

FIG. 2 is a side elevational view;

FIG. 3 is a top plan view; and

FIG. 4 is a bottom plan view.

I claim:

The ornamental design for a dispensing container for vitamins or the like, as shown.
